NONCODE ALARM SIGNAL SYSTEM

John H. Wheelock, Fitzwilliam, N. H., assignor to
 Signal Engineering & Manufacturing Company,
 New York, N. Y., a corporation of Massachusetts

Application June 24, 1936, Serial No. 86,921

9 Claims. (Cl. 177—360)

The present invention relates to alarm signal systems, particularly fire alarm systems, embodying a number of bells or other signals adapted to be sounded or otherwise operated in response to the actuation of any one of a number of separate alarm sending stations, such alarm systems being commonly installed in schools, factories, hotels and other large buildings.

In the installation and operation of alarm signal systems, it is necessary to have continuous electrical supervision of the various circuits and pieces of apparatus embodied in the system, so that any abnormal circuit condition, such as the occurrence of a break or ground will be immediately called to attention upon the operation of a special trouble signal, distinct from the alarm signals. Furthermore, it is most essential that the alarm signals should not be operated to give a false alarm upon the occurrence of any of the abnormal conditions that are noted above.

In my co-pending application, Serial No. 86,512 filed June 22, 1936, there is shown and described an alarm signal system of the above indicated type, which system is particularly characterized by the utilization of a single winding for the operation and supervision of the system, thereby greatly simplifying the system from the standpoint of installation and maintenance. The system disclosed in the aforesaid co-pending application, is responsive to the actuation of any one of a number of sending stations having different code designations, with any given station serving to cause some or all of the signals of the system to give a distinctive alarm, in accordance with the code designation of that particular station.

The present invention relates to an alarm signal system operating on the same general principle as the system disclosed in the aforesaid co-pending application, with all the signals giving the same alarm in response to the actuation of any one of a number of identical noncode sending stations. The system of the present invention also contemplates the utilization of means for causing all the signals to give a common master code, such as a repeated sequence of signal impulses, in response to the actuation of any noncode sending station, as well as to provide for the sending of distinctive master codes, in accordance with the location of an actuated noncode sending station in a particular section of the system. The above and other advantageous features of the invention will hereinafter more fully appear from the following description with reference to the accompanying drawings, in which:

Fig. 1 is a schematic view illustrating the sys-

tem in its normal condition, with continuous electrical supervision of its various circuits.

Fig. 2 is a schematic view similar to Fig. 1, illustrating the sending of an alarm upon actuation of one of the noncode sending stations.

Figs. 3 and 4 are schematic views similar to Figs. 1 and 2, illustrating the functioning of the system for sending a master code, in response to the actuation of any one of the noncode sending stations.

Fig. 5 is a view in front elevation, showing the construction of the circuit controlling device embodied in the system.

Fig. 6 is a view in side elevation of the device of Fig. 5.

Figs. 7 and 8 are schematic views, illustrating the functioning of the system for sending different master codes, in accordance with the location of the actuated noncode sending station.

Like reference characters refer to like parts in the different figures.

Referring first to Fig. 1, the signals 1, which are adapted to be sounded or otherwise electrically operated for giving an alarm are shown, for purposes of illustration, as being of the single-stroke solenoid type, with each signal providing an operating winding 2 within which moves a magnetic striker 2a. The windings 2 of the signals 1 are adapted to be connected in sections across the supply mains 3 and 4, with balancing resistors 5 between the sections, by means of a number of pairs of relatively movable contacts 6 and 7, forming part of a master controller, generally designated by the reference character A.

Referring to Figs. 5 and 6, the master controller A comprises a magnetic core 8, one leg of which is surrounded by an energizing winding 9, while the lower end of the other core leg supports a main armature 10 and an auxiliary armature 11, movable independently of the main armature. The main armature carries a bar 12, on which are mounted a number of contacts 6, corresponding to the movable contacts of the several sets shown in Fig. 1 for controlling energization of the signal windings 2. These contacts 6 are in the form of arms insulated from the bar 12 at 13 and cooperate with the stationary contacts 7 mounted on an insulating base 14 of the master controller A. Therefore, closure of the main armature 10, in response to energization of the winding 9, is adapted to simultaneously energize the signal windings 2, in sections, according to the connection of the several pairs of contacts 6 and 7 to the signal windings and to the supply mains 3 and 4.

Referring again to Fig. 1, the winding 9 of the master controller A is shown as having one terminal thereof connected to the supply main 3, while the other terminal thereof is connected in series to one end of the thermal element 15 of an automatic circuit interrupter of the type shown in the Hanel Patent No. 1,868,500, issued July 26, 1932. The interrupter is shown diagrammatically as consisting of a pivoted arm 16 connected to the other end of the thermal element 15, with the initial tension of the element 15 maintaining the arm 16 in engagement with a stationary contact 17. Upon the passage of a predetermined current through the thermal element 15, its heating and expansion permits a spring 16a to turn the arm 16 about its pivot to disengage stationary contact 17, whereupon current no longer flows through the element 15. The resulting cooling and contraction of the element 15 causes the arm 16 to re-engage contact 17, whereupon the cycle is repeated to cause the interrupter to make and break the circuit of the element 15 so long as sufficient current flows through the element to cause its expansion.

The stationary contact 17 of the thermal element 15 is connected in series with a number of alarm sending stations S, of the noncode type, disposed in various locations throughout the system. Each sending station S provides independent pairs of spaced stationary contacts 18, 19 and 20, 21 and in the normal non-operating condition of the station a circuit is maintained between the contacts 18 and 19 by a bridging member 22, while a second bridging member 23, insulated from member 22, maintains a circuit between contacts 20 and 21. The showing of the station, referred to above, is entirely diagrammatic and it will be readily understood that a station of this character can be constructed in various ways in order to accomplish the results contemplated by my invention. In the illustrated embodiment of a station S, the breaking of a glass G, permits a spring-actuated plunger P to turn the bridging members 22 and 23 into the position of Fig. 2, the bridging members remaining in this position until the glass at the operated station has been replaced.

Normally, all the contacts 18 and 19 of the several stations S are connected in series through the bridging members 22, and the contact 19 of the station farthest removed from the controller winding 9 in the circuit, is connected through a station conductor 24 to a controlling resistor 25. The resistor 25 is connected to the signal windings 2, and the winding 2 of the last signal section is connected to the bridged station contacts 20 and 21 by conductor 26. The nearest station contact 21 is connected to supply main 4 through a conductor 27 and resistor 28 and normally, a small supervisory current traverses the parts of the system described thus far as follows:

Beginning at the supply main 4, the supervisory current flows through the resistor 28, conductor 27, station contacts 21, 20 and conductor 26 to the windings 2 and resistors 5 of the several sections of signals 1. The current then passes through the controlling resistor 25 and conductor 24 to the bridged contacts 19 and 18 of the several stations S, and from thence through the thermal element 15 and the controller winding 9, to the grounded supply main 3. The value of the supervisory current is such as to energize the winding 9 just enough to attract and hold up the auxiliary armature 11, while the main armature 10 remains down; therefore, the system remains in

supervised condition, with the supervisory current traversing all essential parts of the system which are depended upon to cause the signals to send a continuous noncode alarm, in response to the actuation of any one of the sending stations S, as will next be described.

Operation of alarm signals

Whenever the glass G, at any one of the stations S is broken, for the purpose of sending an alarm, the plunger P turns the bridging member 22 into engagement with the contacts 18 and 21, while member 23 engages only contact 20, as shown in Fig. 2. When this occurs, the resistor 25 and signal windings 2 are cut out of the circuit at the unengaged contact 19 of the actuated station, and the increased current flowing through the master controller winding 9 directly from supply main 4, pulls up the main armature 10 and closes all controller contacts 6 and 7. Upon closure of the controller contacts, current flows from the supply main 4 through a conductor 29 leading to the stationary contacts 7 at the left of the winding 9, from which contacts signal operating current may follow two paths. One path includes a conductor 30a, leading to the first section of signals 1 and from then through a conductor 31a to the closed controller contacts at the right of the winding to the grounded supply main 3, while a second current path for the other sections of signals 1 is established through a conductor 30b and the conductors 31a and 31b.

The closing of the controller contacts, upon full energization of the controller winding 9 also establishes a circuit for the interruptor through a conductor 32, and this circuit permits the flow of a greatly increased current through the thermal element 15. Therefore, immediately following the sending of the first signal impulse upon closure of the controller contacts, the thermal element 15 starts to heat up and expand until the spring 16a acting on the arm 16 disengages the arm from contact 17. When this occurs, the winding 9 is completely de-energized, whereupon the armature 10 falls and the controller contacts are opened, followed by cooling and contraction of the thermal element 15 to reengage arm 16 with contact 17. Since the resistor 25 is still maintained out of the circuit through the bridged contacts 18 and 21 at the actuated station, the winding 9 again pulls up the armature 10 to give a second signal impulse, followed by expansion of the thermal element 15 to again de-energize the controller. Therefore, as long as the contacts 18 and 21 at the actuated station remain bridged, the signal windings 2 will be intermittently energized and de-energized to give successive signal impulses spaced at regular intervals, without any code designation.

The operation of the signals will continue in the manner described above until the glass at the actuated station is replaced, thereby unbridging the contacts 18 and 21 and reinserting resistor 25, signal windings 2 and resistors 5 in circuit with the bridged contacts 18, 19 and 20, 21. This restores the entire system to the supervised condition of Fig. 1, in readiness for giving another alarm, or to indicate any abnormal circuit condition through operation of a trouble signal, as will next be described.

Indication of abnormal circuit condition

As previously pointed out, the controller A 75

provides an auxiliary armature 11, and as long as supervisory current traverses the winding, this armature 11 is held up. With the armature 11 in its raised position, a rod 33 serves to hold a movable bridging member 34a in engagement with spaced stationary contacts 34. The contacts 34 are in circuit between a resistor 35 connected to main 3 and one terminal of the operating winding 36' of an auxiliary trouble signal, the other terminal of which is connected to supply main 4. Therefore, as long as the armature 11 holds contacts 34 bridged, the trouble signal winding 36' will be traversed by only a supervisory current just sufficient to hold a plunger 36'a out of engagement with open contacts 37', shunted across a resistor 35 in circuit with the winding 36 of a main trouble signal. Upon the occurrence of a break or a ground in the circuits of the signals 1, the sending stations S, or in the circuit of the thermal element 15, the auxiliary armature 11 will fall, thereby opening the contacts 34 to cause deenergization of winding 36' and closure of contacts 37'. This short circuits resistor 35 and causes energization of the main trouble signal from source B, all as disclosed in my aforesaid co-pending application, Serial No. 86,512 as well as in my Patent No. 2,170,104, issued August 22, 1939. Additional trouble contacts 57 are held closed while armature 10 is down, as hereinafter described with reference to Fig. 4.

As previously pointed out, the system of the present invention is characterized by the fact that the signals 1 cannot operate upon the occurrence of an abnormal circuit condition, such as a break or ground. This is primarily due to the fact that the signals 1 can only be energized upon closure of the controller contacts 6 and, obviously, the main armature 10 cannot pull up upon the occurrence of a break or ground in the signal and station circuits. Upon the occurrence of a ground in these circuits, the presence of the resistor 28 limits the current flowing through any of the windings 2 to such a low value as to prevent operation of the signals, so that closure of the main controller contacts is the only way in which sufficient current can flow through the signal windings 2 to fully energize them. Therefore, by the present invention there is provided a completely supervised signal alarm system of the noncode continuous type, and the manner in which the system may be extended, without substantial change, to operate in conjunction with means for sending a master code by actuation of noncode stations, will next be described.

Operation of alarm signals with master code

Referring now to Fig. 3, there is shown an extension of the system, wherein the essential elements, such as the controller winding 9, thermal element 15, sending stations S and windings 2, are connected in substantially the same manner as previously described, with reference to Fig. 1. In addition, the master controller A provides a stepping mechanism operated by the main armature 10 through a pivotally connected rod 38, carrying a pawl 39 at its upper end. The pawl 39 cooperates with the teeth 40a of a ratchet wheel 40, so that each upward movement of the rod 38, in response to full energization of the winding 9, results in turning a shaft 41, carrying ratchet wheel 40, through a predetermined angle. The shaft 41 carries a master code wheel 42, providing a number of projections 42a, each hav-

ing a peripheral displacement corresponding to several teeth 40a on the ratchet wheel 40.

The supply main 4 is connected by a conductor 43 to a stationary contact 44 that is spaced from a movable contact 45, having one end bearing on the periphery of the master code wheel 42. The contact 44 is connected to a contact 46, movable with the contact 45, although insulated therefrom at 47. The contact 46 is spaced from a stationary contact 48, and the contacts 48 and 45 are connected to the different sections of signal windings 2, by means of conductors 49a and 49b, respectively.

The supervisory circuit of the system of Fig. 3 is substantially the same as that previously described with reference to Fig. 1, the current from the main 4 traversing the resistor 28, conductor 27 and bridged station contacts 21 and 20. The current then flows through station conductor 26 to the signal windings 2. From the signals 1, supervisory current flows through the controlling resistor 25, station conductor 24, bridged station contacts 19 and 18, thermal element 15 and controller winding 9, to the grounded main 3. The value of supervisory current is such as to energize the winding 9 just enough to attract and hold up the auxiliary armature 11 while the main armature 10 remains down, with the pawl 39 in engagement with a ratchet tooth 40a, in readiness to turn the shaft 41, upon full energization of the winding 9.

Whenever the glass G at one of the stations S is broken, for the purpose of sending an alarm, the bridging member 22 is moved into engagement with the contacts 18 and 21. When this occurs, a circuit is established from the supply main 4 through the conductor 27 direct through the thermal element 15 and controller winding 9, the resistor 25 and signal windings 2 being entirely removed from the circuit of the controller winding 9. The increased current through the station contacts 18 and 21 fully energizes the controller winding 9 and, as the armature 10 pulls up, the pawl 39 turns the shaft 41 through one step. This results in closing contacts 44, 45 and 46, 48, by the code wheel projection 42a, and as the armature 10 completes its upward movement, controller contacts 6 and 7 are closed. Therefore, the first pull up of the main armature 10 establishes a number of circuits, as follows:

Closure of the contacts 44, 45 and 46, 48 prepares circuits from the supply main 4 through the conductors 49a and 49b to the signal windings, which circuits are completed through the conductors 31a and 31b leading to the closed right-hand controller contacts 6 and 7, and the supply main 3, thereby operating the signals 1. Closure of the left-hand controller contacts 6 and 7, also establishes a direct circuit from the supply main 4 and conductors 43 and 32, to the thermal element 15, and the resulting heating and expansion of the latter then causes the contacts 16 and 17 to open and deenergize the controller winding 9. As the armature 10 falls, the pawl 39 is moved into position, in engagement with the next ratchet tooth 40a.

Upon cooling and contraction of the thermal element 15, reclosure of contacts 16 and 17 again fully energizes the winding 9, since a direct circuit through the winding 9 from the main 4 is still maintained through the closed station contacts 18 and 21. The armature 10 again pulls up to turn the shaft 41 through another step, and causes the signals 1 to be operated again through

the circuits previously traced. The projections 42a on the master code wheel 42, each have a peripheral displacement equal to a number of ratchet teeth, four as shown, so that the signals 1 will be operated in accordance with a predetermined time or rhythm, such as "one-two-three-four"—"one-two-three-four," that is, four signal impulses, then a pause, followed by four more evenly spaced impulses. By such timing is 10 meant a "master code" which is always the same, in response to the actuation of any station S, as distinguished from a distinctive code for each individual station, as disclosed in my aforesaid co-pending application, Serial No. 86,512.

15 Following the actuation of a station S, the master code sequence will be repeated by the signals 1 as long as the glass G remains broken and the station contacts 18 and 21 are bridged by the member 22. In order to restore the system to the condition of supervision, it is only necessary to replace the glass at the actuated station. After this the signals continue to operate until a notch 50a on a disk 50 carried by shaft 41 causes contacts 51 to open. This breaks 25 a circuit to the thermal element 15, so that shaft 41 comes to rest in the position of Fig. 3, with supervisory current traversing the bridged contacts 18, 19 and 20, 21, respectively.

In Fig. 4, the system is shown with the provision of means for limiting the number of master code sequences given by the signals in response to the actuation of a station S. To this end, a counter-shaft 41a is connected by reduction gearing R to the shaft 41, the ratio of the gearing being such that the shaft 41 will make several revolutions for each complete revolution of the counter-shaft 41a. A control disk 52 is mounted on the shaft 41a, and a movable contact 53 normally has its free end received in a notch 54 provided in the disk 52. The contact 53 is connected by a conductor 55 to the thermal element 15, and turning of the disk 52 is adapted to move contact 53 into engagement with a stationary contact 56. A conductor 43a extends 40 from the supply main 4 to contact 56, as well as to contact 44, which is under the control of the master code wheel 42, in the manner previously described with reference to Fig. 3, and the only other difference is that all the stationary controller contacts 7 are connected to the signals through conductors 31a and 31b.

Upon actuation of a station S, the first pull up of the main armature 10 establishes the same signal-operating circuits as described with reference to Fig. 3, and also causes closure of contacts 53 and 56 upon turning the disk 52 through the displacement of one ratchet tooth 40a. Therefore, a direct circuit from main 4 will be maintained through conductors 43a and 55 to the thermal element 15, as long as the contacts 53 and 56 are closed. The resulting expansion and contraction of the thermal element 15 will cause the signals to give a predetermined number of complete master code sequences determined by the ratio of the gearing R. After the shaft 41 has been turned through a number of complete revolutions, the circuit to the thermal element will be broken at the contacts 53 and 56, as the contact 53 enters the notch 54. When this occurs, the thermal element ceases to function, due to the fact that the resistor 28 is then in circuit with the element 15 through the closed contacts 18 and 21, at the actuated station.

Since the main armature 10 will be held up until the glass at the actuated box has been re-

placed, even though the thermal element has ceased to function, the system of Fig. 4 makes provision for calling attention to this condition. To this end, a pair of contacts 57 are included in circuit with the contacts 34 controlling the energizing circuit of the auxiliary trouble signal winding 36'. The contacts 57 are bridged by a member 51a, only when the main armature 10 is in its lower position, see Fig. 5, while the contacts 34 are bridged only when the small armature 11 10 is held up by the flow of supervisory current through the controller winding 9, as before. Therefore, when the armature 10 is held up after the sending of a predetermined number of master code sequences, the main trouble signal will operate to indicate this condition until the system is restored to the condition of supervision shown in Fig. 4, by replacing the broken glass at the actuated station and re-establishing the flow of supervisory current through the bridged station 20 contacts 18, 19 and 20, 21.

As previously pointed out, the system can be further extended to cause the sending of multiple master codes, as defined above, in accordance with the location of noncode stations in 25 different sections of the system, and the arrangement and operation of such a system will next be described.

Operation of alarm signals with multiple master code

Referring now to Figs. 7 and 8, a master controller A has its winding 9 connected across mains 3 and 4, in circuit with a thermal element 15, the windings 2 and resistors 5 of one or more sections of signals 1 and resistor 28. The system also provides two or more auxiliary controllers A' and A'', having their windings 9' and 9'' connected to two different series of noncode sending stations S' and S'', located in different sections or floors of the building or buildings which are protected by the system. The stations S' and S'' are identical with the stations S of Fig. 1 and, normally, supervisory circuits are maintained through the bridged contacts 18', 19' and 20', 21', 40 of one section and through bridged contacts 18'', 19'' and 20'', 21'' of the other section in series with resistors 25', 28' and 25'', 28'', respectively. Thus the system presents three separate supervisory circuits, one including all the signals 1, the thermal element 15 and the main controller winding 9; a second circuit including all the stations S' of one section and the auxiliary controller winding 9'; and a third circuit including all the stations S'' of the other section and the controller winding 9''.

The main armature 10 of the master controller A is connected to a shaft 41 through a ratchet wheel 40, in the same manner as previously described, and the shaft 41 carries master code wheels 42' and 42'' having projections arranged for different signal sequences, as will be herein-after described. Movable contacts 58 and 59, bearing on code wheels 42' and 42'', respectively, 65 are adapted to cooperate with stationary contacts 60 and 61, connected to the supply main 3. The contact 58, bearing on code wheel 42', is connected to one of a pair of spaced stationary contacts 62, that are adapted to be closed by movable contact 63, in response to full energization of the winding 9' of auxiliary controller A'. The contact 59 bearing on code wheel 42'', is similarly connected to one of a pair of spaced stationary contacts 64, adapted to be closed by movable contact 65, upon full energization of the 75

second auxiliary controller winding 9''. The upper contacts 62 and 64 of the controllers A' and A'', are connected in parallel to a conductor 66 leading to one right-hand stationary contact 7 of the master controller A, the other stationary contact 7 being connected by a conductor 31 to the signal windings 2. Therefore, connection of the windings 2 to the grounded supply main 3 can be selectively accomplished through operation of either auxiliary controller A' or A'', and its associated code wheel 42' or 42'', as will hereinafter appear.

The terminal of the thermal element 15, farthest removed from the controller winding 9, is connected, through contact 17 and conductor 67, in parallel with contacts 68 and 69 provided by the auxiliary controllers A' and A'', respectively. These contacts 68 and 69 are in pairs, normally spaced apart and the lower the contacts 68 and 20 69 are connected in parallel to the supply main 4 through the conductor 70. The pairs of normally open contacts 68 and 69 are adapted to be momentarily closed and then opened by control members 71' and 71'', in response to full energization of either auxiliary controller winding 9' or 9''. As indicated diagrammatically in Fig. 7, the main armatures 10' and 10'' are adapted to move the control members 71' and 71'', upon upward movement of either armature, and momentary engagement between contacts 68 or 69 can be obtained in any suitable manner. As shown in Fig. 8, a rod 72' connected to the end of armature 10', turns the control member 71' through the space of one tooth 73', to first close 35 and then open the contacts 68, as the armature 10' completes its upward movement.

Let it now be assumed that one of the stations S' in the first section is actuated by breaking its glass. Upon bridging of the stationary contacts 18' and 21', the resistor 25' is cut out of circuit, thereby causing armature 10' to pull up, in response to full energization of the winding 9'. This results in closing contacts 62 and 63, thereby selectively preparing a portion of a circuit, 45 which is later completed to the signal windings 2, through the operation of controller A. As the armature 10' pulls up, the contacts 68 are momentarily closed, thereby short circuiting the signal windings 2 and resistor 28, and causing 50 the main armature 10 of controller A to pull up, as shown in Fig. 8.

Upward movement of the armature 10 turns the shaft 41 through the space of one ratchet tooth 40a, thereby closing contacts 53 and 56, so 55 as to establish a circuit to the thermal element 15 and controller winding 9 from supply main 4, in spite of the opening of the momentary contacts 68 of the auxiliary controller A'. Turning of the code wheel 42' also closes contacts 58 60 and 60 at the first master code projection, thereby further extending the circuit to the supply main 3 from the previously closed contacts 62 and 63 of controller A'. Therefore, closure of the master controller contacts 6 and 7, as the 65 armature 10 completes its upward stroke, causes signal energizing current from main 4 to flow through conductors 30 and 55, signal windings 2, conductors 31 and 66, closed contacts 62 and 63 of the controller A' and closed contacts 58 and 70 60 to main 3, thereby giving the first signal impulse.

Closure of the contacts 53 and 56 by the disk 52, also causes the thermal element 15 to function in the manner previously described, so as to 75 intermittently deenergize and reenergize the

controller winding 9. The successive turning movements thus imparted to the shaft 41 cause the signals 1 to be operated in a sequence determined by the angular displacement of the projections on the master code wheel 42'; in this 5 instance a repeated rhythm corresponding to "one-two-three" — "one-two-three" — "one." Upon operation of a station S' of the other section, momentary bridging of the contacts 69 initiates the same cycle of operation just 10 described, with the exception that the signal windings 2 are energized through the closed contacts 64 and 65 of controller A''. In the latter case, the master code wheel 42'' controls the signal sequence, in accordance with a rhythm corresponding to "one-two-three" — "one-two-three" — "one-two." In other words, the particular master code sequence given by all of the signals 1, in response to actuation of any one of the noncode stations S' or S'', serves as an 15 indication of the particular section in which the actuated station is located.

From the foregoing, it is apparent that by the present invention there is provided an improved alarm signal system, characterized by its ability 20 to operate signals, in response to the actuation of any one of a number of identical noncode sending stations. The signals may be operated either continuously, or for a limited period, and on a master code basis, if desired. Furthermore, 25 the system can be readily expanded to cause the operation of the signals in accordance with a distinctive master code, to designate the general location of the actuated station.

In all the various modifications of the system, 30 all parts are under continuous supervision, and the occurrence of a fault in any signal circuit will not prevent operation of a station. Furthermore, the signals are so sectionalized that the occurrence of a fault in one section will not 35 prevent operation of the other sections of signals.

I claim:

1. In an electric signaling system, the combination with transmitting stations, each including contacts, with connections therebetween, and means for changing said contact connections upon the actuation of a station, signals of the single-stroke type, an interrupter operable to alternately open and close a circuit therethrough, when traversed by a current of given 45 value, a controller having a winding in a closed supervisory circuit including said station contacts, with their connections, signals and said interrupter, and signal energizing circuits including normally open contacts operable by said controller, with the flow of supervisory current through said controller winding being insufficient to cause closure of its contacts, or to operate said signals or said interrupter, of means responsive to a change in the connections 50 of the contacts of an actuated station to increase the current flow through said interrupter to such a value, as to cause said controller to intermittently operate said signals.

2. In an electric signaling system, the combination with transmitting stations, each including contacts, with connections therebetween, and means for changing said contact connections upon the actuation of a station, signals of the single-stroke type, an interrupter operable to alternately open and close a circuit therethrough, when traversed by a current of given value, a controller having a winding in a closed supervisory circuit including said station contacts, with their connections, signals and said interrupter, and 70 75

- signal energizing circuits including normally open contacts operable by said controller, with the flow of supervisory current through said controller winding being insufficient to cause closure of its contacts, or to operate said signals or said interrupter, of means responsive to a change in the connections of the contacts of an actuated station, to increase the current flow through said interrupter to such a value, as to cause successive energizations and deenergizations of said controller winding, with resulting intermittent operation of said signals by the opening and closing of said controller contacts.
3. In an electric signaling system, the combination with transmitting stations, each including contacts, with connections therebetween, and means for changing said contact connections upon the actuation of a station, signals of the single-stroke type, an interrupter operable to alternately open and close a circuit therethrough, when traversed by a current of given value, a controller having a winding in a closed supervisory circuit including said station contacts, with their connections, signals and said interrupter, and signal energizing circuits including normally open contacts operable by said controller, with the flow of supervisory current through said controller winding being insufficient to cause closure of its contacts, or to operate said signals or said interrupter, of means responsive to a change in the connections of the contacts of an actuated station, to increase the current flow through said interrupter to such a value as to cause said controller to intermittently operate said signals, and means for rendering said interrupter non-operative, after said signals have operated over a predetermined period.
4. In an electric signaling system, the combination with transmitting stations, each including contacts, with connections therebetween, and means for changing said contact connections upon actuation of a station, signals, an interrupter operable to alternately open and close a circuit therethrough, when traversed by a current of given value, a controller having a winding in a closed supervisory circuit including said station contacts, with their connections, signals and said interrupter, signal energizing circuits including, in part, normally open contacts operable by said controller, and a stepping device also operable by said controller winding and providing contacts in one of said signal energizing circuits, with the flow of supervisory current through said controller winding being insufficient to cause closure of its contacts, or to operate said stepper, said signals, or said interrupter, of means responsive to a change in the connections of the contacts of an actuated station, to increase the current flow through said interrupter to such a value as to cause said controller winding to successively open and close both the signal energizing circuit contacts and the contacts under control of said stepping device.
5. In an electric signaling system, the combination with transmitting stations, each including contacts, with connections therebetween, and means for changing said contact connections upon actuation of a station, signals, an interrupter operable to alternately open and close a circuit therethrough, when traversed by a current of a given value, a controller having a winding in a closed supervisory circuit including said station contacts, with their connections, signals and said interrupter, signal energizing circuits including, in part, normally open contacts oper-

able by said controller, and a stepping device also operable by said controller winding and providing contacts in one of said signal energizing circuits, with the flow of supervisory current through said controller winding being insufficient to cause closure of its contacts, or to operate said stepper, said signals, or said interrupter, of means responsive to a change in the connections of the contacts of an actuated station, to increase the current flow through said interrupter to such a value, as to cause said controller winding to energize said signals, in accordance with the opening and closing of the contacts under the control of said stepping device.

6. In an electric signaling system, the combination with transmitting stations, each including contacts, with connections therebetween, and means for changing said contact connections upon actuation of a station, signals, an interrupter operable to alternately open and close a circuit therethrough, when traversed by a current of given value, a controller having a winding in a closed supervisory circuit including said station contacts, with their connections, signals and said interrupter, signal energizing circuits including, in part, normally open contacts operable by said controller, and a stepping device also operable by said controller winding and providing contacts in one of said signal energizing circuits, with the flow of supervisory current through said controller winding being insufficient to cause closure of its contacts, or to operate said stepper, said signals, or said interrupter, of means responsive to a change in the connections of the contacts of an actuated station, to increase the current flow through said interrupter to such a value, as to cause said controller winding to energize said signals in accordance with a sequence determined by a master code wheel driven by said stepper.

7. In an electric signaling system, the combination with transmitting stations, each including contacts, with connections therebetween, and means for changing said contact connections upon actuation of a station, signals, an interrupter operable to alternately open and close a circuit therethrough, when traversed by a current of given value, a controller having a winding in a closed supervisory circuit including said station contacts, with their connections, signals and said interrupter, signal energizing circuits including, in part, normally open contacts operable by said controller, and a stepping device also operable by said controller winding and providing contacts in one of said signal energizing circuits, with the flow of supervisory current through said controller winding being insufficient to cause closure of its contacts, or to operate said stepper, said signals, or said interrupter, of means responsive to a change in the connections of the contacts of an actuated station, to increase the current flow through said interrupter to such a value, as to cause said controller winding to energize said signals in accordance with the opening and closing of the contacts under the control of said stepping device, and means actuated by said stepping device for discontinuing the energization of said signals after a predetermined period.

8. In an electric signaling system, the combination with transmitting stations arranged in sections and each including contacts with connections therebetween and means for changing said contact connections upon actuation of a

station, signals, an interrupter operable to alternately open and close a circuit therethrough when traversed by a current of given value, a controller having a winding in a closed supervisory circuit including said signals and said interrupter, signal energizing circuits including, in part, normally open contacts operable by said controller, and a stepping device also operable by said controller winding and providing different sets of contacts adapted to be included in said signal energizing circuits, with the flow of supervisory current through said controller winding being insufficient to cause closure of its contacts or to operate said stepper, said signals or said interrupter, of means responsive to a change in the connections of the contacts of an actuated station in one section to increase the current flow through said interrupter to such a value as to cause said controller winding to successively open and close the signal energizing circuit contacts and to include one set of stepper contacts in circuit therewith while maintaining the other set of stepper contacts out of circuit.

9. In an electric signaling system, the combination with transmitting stations arranged in sections and each including contacts with connections therebetween and means for changing

said contact connections upon actuation of a station, signals, an interrupter operable to alternately open and close a circuit therethrough when traversed by a current of given value, a controller having a winding in a closed supervisory circuit including said signals and said interrupter, signal energizing circuits including, in part, normally open contacts operable by said controller and a stepping device also operable by said controller winding and providing different sets of contacts adapted to be included in said signal energizing circuits, with the flow of supervisory current through said controller winding being insufficient to cause closure of its contacts or to operate said stepper, said signals or said interrupter, of means responsive to the actuation of a station in one of said sections to connect one set of stepper contacts in said signal energizing circuits and to increase the current flow through said interrupter to such a value as to cause said controller winding to successively open and close the signal energizing circuit contacts to operate said signals in accordance with a sequence determined by operation of the selected stepper contacts. 25

JOHN H. WHEELOCK.
